MACHINE AND METHOD FOR THE PRODUCTION OF BLASTING DETONATORS AND IMPROVED BLASTING DETONATORS

Philip C. Bishop, Saltcoats, Scotland, assignor to Imperial Chemical Industries Limited, a corporation of Great Britain

Application May 22, 1951, Serial No. 227,574

Claims priority, application Great Britain June 2, 1950

3 Claims. (Cl. 86—39)

The present invention relates to an improved method and machine for the production of blasting detonators of the kind wherein a portion of the wall of the ductile metal casing in the vicinity of the mouth is pressed against a closure member of a resiliently deformable nature inserted into the mouth of the casing, and to improved detonators made thereby.

The invention is applicable for instance to the manufacture of the so-called capped fuses which consist essentially of a plain detonator firmly attached to a length of safety fuse extending from the exterior through the mouth of the detonator casing so that one end of it is in close proximity to the detonator charge, and also to the production of electric detonators of the kind in which a portion of the detonator casing in the vicinity of the mouth is forced into contact with a resiliently deformable plug through which pass insulated conductors leading to an electric igniter positioned within the casing for ignition of the detonator charge.

Hitherto in the production of capped fuses and in the main of electric detonators of the kind described the method of attachment of the detonator casing to the resilient element inserted through its mouth has consisted in crimping the metal of the detonator casing into contact with the said resilient member, by which we mean that a tool is applied to the exterior of the detonator casing that has the effect of making sharp indentations around the periphery of that portion of the casing, in order to ensure that the detonator and the element protruding from it, i. e. the fuse or the conductors, will not easily be torn apart from one another.

Various types of crimp are used in practice, and depending in part on the mechanical strength and the degree of waterproofness of the assembly required, the number and position of the indentations in the area where they are made shows considerable variation, but it is always a characteristic of the method of crimping that the metal of the casing undergoes sharp distortions, which constitute a mechanical weakness. Thus the sharp distortions of the metal may lead to the development of cracks in the metal of the casing especially if the metal is not of uniform physical properties, and their existence may escape notice, with the result that the waterproof properties of the detonator suffer, with consequent risk of failure to function even if the mechanical strength of the assembly appears to be satisfactory.

According to the present invention the method for providing a detonator with a resilient closure member comprises necking the mouth portion of the detonator casing on to the closure member.

If desired the closure member is of smaller diameter than the diameter of the mouth portion of the detonator casing before necking.

Furthermore if desired the closure member passes through the mouth of the detonator and can be for example a length of safety fuse.

By "neck" is to be understood a portion of a detonator

2

tube having a reduced diameter and at least approximately the original circular cross-section.

In the resulting detonators where the surface of the metal of the casing presses into contact with the resilient member there are no places where the metal is doubled back on itself. Thus the liability to the development of cracks or weaknesses in the metal is greatly reduced, and the mechanical strength and waterproofness of the joint are highly satisfactory. In fact the waterproofness attainable can be greater than is necessary for most purposes. For example it has been experimentally ascertained that the said joints can withstand an external water pressure of 200 lbs./sq. inch without leakage.

It will be understood that the contour of the necked surface may be varied for instance by providing two or more necks connected by surfaces of gradually or progressively diminishing diameter towards the mouth end of the detonator.

A detonator according to the present invention therefore has a neck in the mouth portion of the detonator casing and a resilient closure member in said neck.

If desired the resilient closure member passes through the mouth of the detonator casing as for example where the resilient closure member is a length of safety fuse.

25 Apparatus according to the present invention comprises a pusher in combination with a die formed from two portions which are adapted to be moved apart and to be brought together by movements having components at right angles to the path of said pusher and when apart to be sufficiently separated to allow a detonator to be inserted or withdrawn from its forward end and when together to leave a small axial opening at its forward end and to form at least one surface progressively converging forwardly, said pusher being positioned at the rearward 30 end of said die.

If desired the said two portions when together form a longitudinal channel commencing at the rearward end of the die.

One form of apparatus suitable for the production of 40 detonators according to the invention comprises longitudinally reciprocable portions which in their forward position form together an axially channelled exteriorly frusto-conical die having at least one internal surface progressively converging forwardly and a small axial opening at its forward end and in their rearward position have a separation sufficient to allow a detonator to be inserted or withdrawn through the forward end, a fixed annular guide having a frusto-conical surface adapted to bring together said die portions moving forwardly within it to support said portions over the area of their frusto-conical surface when in the forward position, springs adapted to separate said die portions as they move backwards within said annular guide, an axially channelled stem attached to said die of sufficient diameter to accommodate a detonator tube, and a reciprocating pusher.

Preferably the reciprocating pusher is timed with the motion of said stem so as to permit a detonator tube to fall into the channel of said stem when said stem and die portions are in retracted position and to push the detonator tube forward during the forward motion of said stem and die portions.

In accordance with this form of apparatus the stem of the die is slotted so that when said stem and the pusher are in retracted position the slot is in line with a supply of longitudinally orientated and superposed detonator tubes forwardly of the pusher.

70 If it is desired that the necked portion of the detonator should have two or more necks connected by surfaces of gradually or progressively forwardly converging contour they may either all be formed in a single operation by suitably contouring the forward portion of the channel of the die portions or the machine may incorporate a plu-

rality of units whereof the die channels are each formed with one of the desired contours, and if desired it may be arranged that the detonator necked on the first unit may be transferred to the die of the next unit in its open position by suitable means.

If it is desired to produce a smaller neck than can conveniently be done in one operation then an assembly can be provided consisting of successive apparatus each having a die of larger diameter than the next one and means to enable detonators to be transferred from one said apparatus to its next one.

The apparatus of the invention may be set either horizontally or vertically, and where there is used a loose igniting charge instead of a matchhead would be set vertically so that the mouth of the detonator tube points upwards.

One form of apparatus according to the invention is illustrated by reference to the diagrammatic drawings accompanying the specification whereof Fig. 1 is a longitudinal axial section in a vertical plane showing the die in its closed position with a necked detonator enclosed therein at the end of a working stroke. Fig. 2 is a similar section showing the die in its open position with the pusher retracted and a detonator tube in front of the pusher and also an electric fuse assembly having its leading wires passing through a resilient plug ready to be assembled with the detonator tube. Fig. 3 is an end elevation as seen from the front of a portion of the apparatus illustrated in Fig. 2 and Fig. 4 is a similar end elevation corresponding to Fig. 1. Fig. 5 is a longitudinal axial section in a horizontal plane corresponding to Fig. 1. Fig. 6 is a detail showing the shape of a die having two tapering portions and Fig. 7 is a detail showing a finished electric detonator, these two figures being on a larger scale than Figs. 1-5.

In Figs. 1-5, 1 is the body of the machine and 2 a flange thereon providing a base for the machine. 3 are parallel arms formed integral with an annular guide 4 having a frusto-conical internal surface. 5 is a horizontally split externally frusto-conical die the halves of which are semi-cylindrically axially channeled for the greater part of their length and at their forward portion are so contoured as to provide when the die is closed a channel of the desired shape for the necked detonator, terminating in a somewhat flaring mouth. These portions of the die are drilled with vertical holes 6 near their centre of gravity so as to accommodate springs 7 normally in compression tending to urge the two halves apart from one another. These portions of the die are dove-tailed into an axially channelled reciprocable stem 8 which prevents the halves of the die from relative motion horizontally but permits them to move apart from one another in a vertical plane, this stem having integral rearward extension forks 9 in which cross-head 11 is reciprocated axially by a power operated piston. 31 is a flanged ring joining the end of the forks 9 and providing a stop for the cross-head 11. When the piston 10 is retracted this cross-head pulls back the forks 9 and the integral stem 8 and with them the halves of the die 5 and these are forced apart during this motion by the springs 7. The frusto-conical shape of the exterior of the die 5 and the internal surface of the constrictor guide 4 are of the same taper and maintain the halves of the die in parallel relation. The flanged ring 31 during its rearward motion also compresses a spring 12 against an outer bearing 13. A slot 14 is provided in the body 1 through which a bolt 15 is screwed into a channel drilled in one of the forks 9 so as to prevent the stem 8 from rotating in a vertical plane. 16 is another slot in the body forming part of the termination of a magazine chamber. 17 is a slot in the stem 8 from which a detonator tube falls into the axial channel thereof when the piston 10 is retracted, and into which another detonator falls when retraction of the stem 8 brings said slot 17 into alignment with slot 16. The detonator tubes 19 are presented with their closed ends

rearward and their open ends forward. 20 is a coupling to driving means (not shown) for operating the cross-head 11 and piston 10. 21 is an adjustable stop motion nut.

5 The electric fuse assembly consisting of insulated leading wires 22 passing through a cylindrical plug 24 of resiliently deformable rubber-like material and terminating in a matchhead 23 is introduced into the die from the front in its retracted position and may be held approximately in the desired position beyond the converging portion. The succeeding forward stroke of the die causes its halves to come together and thus traps the plug 24 beyond the converging portion of the die. The die however does not necessarily grip the plug tightly. The forward stroke of the piston behind the detonator tube 19 ultimately causes the mouth of the detonator tube to reach the plug and carry it forward until it meets resistance due to the convergence of the die. The tube mouth then rides over the plug and grips it when forced into the converging portion of the die. The tube and plug then advance together through the narrow portion of the die, thus forming the neck containing the plug. The original position of the plug in the channel is therefore a matter of indifference as long as it is beyond the converging portion of the channel. The retraction of the piston and with it the die enables another detonator tube to fall into position in the channel of the stem 8 and opens up the die and enables the necked detonator tube to be withdrawn from the front.

In Fig. 6 the contour of the cylindrical part of the die channel is shown by 25, that of one of the converging portions by 26, which gives place to a smaller cylindrical portion 27 and then to a smaller converging portion 28 leading to an even smaller cylindrical portion 29 which is outwardly flared as shown at 30.

35 What I claim is:

1. Apparatus for closing the open end of a detonator tube around a resilient closing element comprising a divided die mounted for movement between an open position and a closed position, said die in its closed position defining a channel having a longitudinally extending detonator tube receiving portion and an inwardly tapered portion communicating therewith, means for moving said die into its closed position, means movable through an operative path for effecting a relative longitudinal movement between said die and a detonator tube positioned adjacent thereto, means operatively associated with said relative movement effecting means and said die closing means for actuating the latter to close said die in response to the initial movement of said relative movement effecting means through said operative path, said relative movement effecting means being operable upon further movement through said operative path to effect an interengaging relative longitudinal movement between the inwardly tapered portion of said die channel and the open end of the detonator tube so as to deform the latter inwardly into engagement with a resilient closing element disposed therein.

2. Apparatus for closing the open end of a detonator tube around a resilient closing element comprising a divided die movable between an open position and a closed position, guide means receiving said die, a driving member connected with said die for reciprocating the latter within said guide means to effect the movement of said die into its open and closed positions, said die in its closed position defining a channel having a detonator tube receiving portion and an inwardly tapered portion communicating therewith, a plunger slidably mounted within said driving member for movement toward and away from said die, and means operatively connected between said plunger and said driving member for moving the latter to effect the movement of said die into its closed position in response to the initial movement of said plunger toward said die, said plunger being operable upon further movement thereof toward said die to force the open end of a detonator tube dis-

posed within the receiving portion of the die channel into engagement with the inwardly tapered portion thereof whereby the open end is deformed inwardly into engagement with a resilient closing element disposed therein.

3. Apparatus as defined in claim 2 wherein said die comprises a pair of die elements having a spring therebetween normally urging the same radially apart and wherein the inner end of each die element is connected with said driving member by means of a dove tail connection operable to prevent relative longitudinal movement between the die elements and the driving member and to permit radial movement of the die elements with respect to each other. 10
